(57) **CLAIM**

The ornamental design for a shelf and corbel, as shown and described.

DESCRIPTION

FIG. 1 is a front perspective view of a shelf and corbel, according to the first embodiment of the invention;

FIG. 2 is a front perspective view of a shelf and corbel, according to the second embodiment of the invention;

FIG. 3 is a rear perspective view of FIG. 1;

FIG. 4 is a rear perspective view of FIG. 2;

FIG. 5 is a side view of FIG. 1;

FIG. 6 is a side view of FIG. 2;

FIG. 7 is a top view of FIG. 1;

FIG. 8 is a top view of FIG. 2;

FIG. 9 is a bottom view of FIG. 1;

FIG. 10 is a bottom view of FIG. 2;

FIG. 11 is a front view of FIGS. 1 & 2; and,

FIG. 12 is a rear view of FIG. 2.

The broken lines shown in FIGS. 1, 3, 5, 7 & 9 are for illustrative purposes only and form no part of the claimed design.
